HYGROMETER

Don P. Wickersham and Karl Otto Waldvogel,
Urbana, Ohio, assignors to The Johnson Manufacturing Company, Urbana, Ohio, a corporation of Ohio

Application November 23, 1932, Serial No. 644,086
Renewed September 4, 1935

10 Claims. (Cl. 297—1)

This invention relates to improvements in hygrometers, it more particularly relating to that class of hygrometers in which the moisture responsive element is formed of wood or similar fibrous material.

One of the objects of the invention is to provide a hygrometer of the type referred to which will be simple in construction and effective in operation.

10 Another object of the invention is to provide a fibrous moisture absorbing hygroscopic element so constructed as to shorten the fibers of the element to a degree to reduce the time lag in producing humidity indications, but at the same time 15 have imparted to the element the requisite strength to perform the work required in actuating the indicating devices.

Another object is the provision of an improved 20 form of fibrous hygroscopic element of laminated construction, the laminations of which are arranged so as to eliminate any tendency of the element to warp or buckle when expanding.

Another object is the provision of an adjustable, yieldable supporting means for the moisture 25 responsive element whereby damage to the working parts of the instrument is averted in the event of the element becoming saturated with moisture to an extent to cause it to expand beyond a normal limit.

30 Other objects of the invention will appear from the accompanying description.

In the accompanying drawing:

Fig. 1 is a perspective view of the improved 35 hygrometer with a portion of the outer casing broken away so as to show the interior construction.

Fig. 2 is a top plan view also with a portion of the outer casing broken away.

Fig. 3 is a vertical section on the line 3—3 of 40 Fig. 2.

Fig. 4 is an enlarged transverse section on the line 4—4 of Fig. 3.

Fig. 5 is a further enlarged fragmentary vertical section on the line 5—5 of Fig. 3.

45 Fig. 6 is a fragmentary perspective view of an assembly composed of two details of the device.

A large number and variety of materials are 50 hygroscopic, and in practically all instances each material is affected to a degree directly proportional to the degree of moisture carried by the air. The effect of vapor on wood is well known, a body formed of wood expanding in all directions whereby its length, breadth and thickness is increased by the absorption of atmospheric 55 vapor. Wood in the form of a plank expands

most noticeably in the direction of its width, and hygroscopic elements have been made in the past to utilize this comparatively great expansion by forming elements from planks by simply sawing a comparatively short section from the end of a 5 plank. The "width" dimension of the plank now corresponds to the "length" dimension of the element, and the element is usually supported at one end while it is connected at the other end to some means of indication.

One of the disadvantages of this type of moisture responsive element is that the element follows the tendency of the plank in expansion, that is, if any portion of a plank is inclined to bow in one direction or the other, an element removed from that portion of the plank would also show a tendency to bow, or perhaps buckle. In other words, elements having the original undisturbed grain of the plank, may or may not expand in the straight line desired, and if only those 20 portions of a plank are selected which do not show a tendency to bow or buckle, the manufacturing cost of the instrument is increased.

The improved element is a laminated structure, composed of a plurality of small sections cemented together, the end grain of each of the sections being disposed as in the case of the simple element cut from the end of the plank, that is, at right angles to the "length" dimension 25 of the element.

30 Referring to the drawing, the improved element is indicated in general at 1, the several sections at 2 and the joints between them at 3.

A simple and preferred method of building up 35 these improved elements is as follows: A plank is sawed lengthwise into strips and alternate strips are inverted side for side and reassembled with cemented joints whereby a laminated plank whose width is equal to the "length" dimension desired for the elements, with the fibers extending in 40 the same direction, but some of which have been inverted end for end with relation to the others, is obtained, after which the elements are sawed from the end of this laminated plank. There is thus formed an improved wooden hygroscopic element which has lost none of the advantage of 45 the simple element, but has the further advantage that the improved element expands in the desired straight line, which may be explained as follows: If a portion of the original plank had 50 a tendency to bow in any direction during expansion, each alternate strip after inversion in retaining its tendency to bow corrects the initial tendency of the uninverted strips by introducing an equal bow in the opposite direction, with the 55

result that an element is obtained which will expand in the general straight line desired. On the other hand, if there was no tendency to bow in the original plank, no tendency to bow is introduced, since there was no deviation to correct.

Hygrometers are sensitive according to the sensitivity of the element. The sensitivity of the element when formed of fibrous material, such as wood, may be increased by shortening the fibers, which amounts to decreasing the vapor penetration distance so that vapor entering from a side does not have far to penetrate before meeting vapor entering from an opposite side. Shortening of the penetration distance may be brought about by decreasing the cross-sectional area, but the probable result would be that the element would not have sufficient strength to actuate a suitable indicating device. Therefore we have adopted a comparatively large H-cross-section for the greater portion of the body of the element, as best seen in Fig. 4, whereby we not only obtain an element of ample strength, but also an element having a high degree of sensitivity. Sensitivity is obtained by milling a deep groove 4 into each of the two opposite sides 5 and 5' of the element, the grooves 4 extending substantially from end to end of the element thereby shortening the greater percentage of the long fibers. In the other two sides 6 and 6' shallower grooves 7 are milled which decrease the length of most of the remaining long fibers, the grooves 7 extending throughout the length of the element. The latter grooves 7 are also employed for another purpose as will now be explained.

The moisture responsive element actuates an arm 8 which is provided with a pointer 9. The arm is pivotally mounted on a hinge pin 10 secured in upstanding ears 11 attached to an out-turned portion 12 of a back-plate 13. The arm is provided with a longitudinal slot extending from a connecting portion 14 at the upper end of the arm to the lower end, leaving the lower end open, so that the element 1 may be slid into the arm, the legs 15 of the arm being slidably fitted in the shallow grooves 7 previously mentioned. The inner edges of the legs 15 are out-turned as shown at 16 (Figs. 4 and 6) to strengthen the arm and form guiding flanges for the element. The lower end of the arm is connected by a member 8' soldered or secured in any suitable manner to the bent portions 8'' which receive the hinge pin 10.

Each end of the element 1 is protected against abrasion by a small metal pad, there being a pad 17 secured to the upper end of the element where contact is made with the lower edge of the connecting portion 14, and a second pad 18 secured to the lower end where the element makes contact with the yieldable supporting means which will now be described.

In effect the arm 8 is partly supported by the element 1 and follows the expansion and contraction thereof, the arm being returned as the element contracts by a return spring 19 (Fig. 1). In turn the element 1 is supported on members attached to the out-turned portion 12 of the back plate and located at one side of the pivotal mounting of the arm 8. In the present instance, the element supporting means is both adjustable and yieldable, the adjustable feature being provided to compensate for the small differences encountered in the manufacture of the moisture responsive elements, while the advantage of the yieldable feature will appear later.

In view of the pivotal mounting of the arm 8 and the disposition of the element supporting means, as seen in Figs. 1 and 5, it should be clear that upon expansion of the element 1 the arm will be moved to the right about the pivot pin 10 and that a reverse movement of the arm will take place when the element is giving up its moisture and contracting. In Fig. 5 the arm is shown at a slightly different angle than is shown in Fig. 1 or Fig. 3. One end of the spring 19 is hooked to a small bar 21 held in the notched fingers 22 of the arm 8, while the lower end of the spring is secured to a spring post 23 fixed to the out-turned member 12.

The purpose of the yieldable support is as follows: The hygrometer scale should be extended so as to indicate saturation at one end and a very dry condition at the other. In the present device the saturation point is obviously at the right end of the scale, since the arm 8 swings in that direction during expansion. There would be no point in allowing the pointer 9 to swing further than the saturation designation, therefore a stop-pin 24 is secured to the back-plate 13 at the proper place to prevent an over-swing of the arm beyond the end of the scale. Thus the pointer will swing to the saturation point when the air reaches that condition, but should the element become water soaked from any cause, the added expansion thereof will be expended in forcing down a spring-pressed plunger 25 which forms a part of the supporting means.

The plunger 25 is slidably fitted and retained in the bore 26 of a thimble 27 which is exteriorly threaded for insertion in an interiorly threaded boss 28 secured to the out-turned member 12, the location being such that the supporting means is on the opposite side of the arm center from the hingable connection of the arm with the member 12. A plunger spring 29 is interposed between the plunger and a plate 30 fixed in the lower portion of the thimble 27. The power of the spring 29 should be somewhat greater than the power of the return spring 19, so that the plunger will be forced from its normal upper position only in the event the element becomes water soaked.

The present scale 31 is calibrated to read in percentages of relative humidity of the air, therefore the extreme right hand end is designated 100 or saturation, while the left hand end denotes a very dry air condition, intermediate points being struck off at proper intervals. The scale is mounted in any suitable manner on the outer surface of an extended member 32 secured to the back plate 13 in proximity to the pointer 9.

The working parts of the instrument are protected by an outer casing 33 removably secured to the back-plate 13, and in the walls of the outer casing are numerous openings 34 to provide free access to the air.

By the foregoing description it will be seen that we have provided a simple, inexpensive and efficient instrument for noting the variations of the air as regards the relative humidity thereof, having a hygroscopic element of sufficiently large cross-sectional area whereby ample power is derived for actuating the indicating means or a simple form of humidity control device, yet with the cross-sectional area so distributed that the greater portion of the fibers are short and the penetration distance is therefore also shortened, resulting in reducing the time lag of the instrument both during a condition of a rising percentage of relative humidity and in a fall thereof.

Having thus described our invention we claim:

1. The method of forming a hygroscopic element consisting in severing a wooden plank lengthwise into a plurality of strips, inverting some of said strips side for side, forming from the strips a laminated plank, and severing cross-wise from said plank a piece to form a hygroscopic element, the length of which is represented by the width of the plank and whose fibers extend at right-angles to the length thereof.
2. The method of forming a hygroscopic element consisting in severing a wooden plank lengthwise into a plurality of strips, inverting some of said strips side for side, forming from the strips a laminated plank, and severing cross-wise from said plank a piece to form a hygroscopic element, the length of which is represented by the width of the plank and whose fibers extend at right-angles to the length thereof, and forming grooves in the sides of said severed piece extending in the direction of the length thereof to decrease the length of the fibers.
3. The method of forming a hygroscopic element consisting in severing a plank lengthwise into a plurality of strips, inverting alternate strips side for side, cementing the strips together to form a laminated plank, severing cross-wise from the laminated plank portions thereof, the length of each of which is represented by the width of the plank and whose fibers extend at right-angles to the length thereof.
4. The method of forming a hygroscopic element consisting in severing a plank lengthwise into a plurality of strips, inverting alternate strips side for side, cementing the strips together to form a laminated plank, severing cross-wise from the laminated plank portions thereof, the length of each of which is represented by the width of the plank and whose fibers extend at right-angles to the length thereof, and grooving the severed portion lengthwise to reduce the length of the fibers.
5. A hygroscopic element formed of laminated wood with the fibers of the laminations all extending at right-angles to the length of the element, said element having grooves extending throughout the length thereof to reduce the length of the fibers without materially decreasing the strength of the element.
6. A hygroscopic element formed of laminated

wood with the fibers of the laminations all extending at right-angles to the length of the element, each laminated portion extending entirely across the width of the element, said element having grooves extending throughout the length thereof to reduce the length of the fibres without materially decreasing the strength of the element.

7. In a hygrometer, an upwardly extending arm having a lower offset portion, a support to which said offset portion is pivotally connected, an elongated expansible and contractible moisture responsive element movably mounted in said arm having its upper end engaging a part of said arm, and a second support for the lower end of said arm removed from the pivotal point of said arm.

8. In a hygrometer, an upwardly extending arm having an elongated recess, an offset portion on the lower end of said arm, a support to which said offset portion is pivotally connected, an elongated expansible and contractible moisture responsive element mounted in the recess of said arm and having grooves to receive portions of said arm to slidably connect the element and arm, the upper end of said element having an engagement with a part of said arm, and a second support for the lower end of said element removed from the pivotal point of said arm.

9. The method of forming a hygroscopic element consisting in severing a plurality of strips of wood lengthwise, inverting at least some of said strips side by side to form from the strips a laminated plank, uniting such inverted strips together, and severing cross-wise from said plank a piece to form a hygroscopic element whose fibers extend at right-angles to the length thereof.

10. The method of forming a hygroscopic element consisting in severing a plurality of strips of wood length-wise, inverting at least some of said strips side by side to form from the strips a laminated plank, uniting such inverted strips together, severing cross-wise from said plank a piece to form a hygroscopic element whose fibers extend at right-angles to the length thereof, and forming grooves in the sides of said severed piece extending in the direction of the length thereof to decrease the length of the fibers.
